(57) **CLAIM**

The ornamental design for a golf club end cap, as shown and described.

DESCRIPTION

This application is related to U.S. patent application Ser. No. 12/813,465 filed on Jun. 10, 2010.

FIG. 1 is a side view of the golf club end cap;

FIG. 2 is a top view thereof;

FIG. 3 is a bottom view thereof;

FIG. 4 is a bottom perspective view thereof;

FIG. 5 is a top perspective view thereof;

FIG. 6 is a side view of a second embodiment of the golf club end cap;

FIG. 7 is a top view of FIG. 6;

FIG. 8 is a bottom view of FIG. 6;

FIG. 9 is a bottom perspective view of FIG. 6; and,

FIG. 10 is a top perspective view of FIG. 6.
